UNITED STATES PATENT OFFICE.

BENJAMIN F. MAYO, OF SALEM, MASSACHUSETTS; ETTA MAYO, EXECUTRIX OF SAID BENJAMIN F. MAYO, DECEASED, ASSIGNOR OF ONE-THIRD TO JAMES A. BROGAN, OF LAWRENCE, MASSACHUSETTS, AND ONE-THIRD TO PATRICK F. BROGAN, OF NEW YORK, N. Y.

HEAT-RESPONSIVE DEVICE.

Application filed February 11, 1918. Serial No. 216,494.

To all whom it may concern:

Be it known that I, BENJAMIN F. MAYO, a citizen of the United States, residing at Salem, in the county of Essex and State of Massachusetts, have invented certain Improvements in Heat-Responsive Devices, of which the following description, in connection with the accompanying drawings, is a specification, like reference characters on 10 the drawings indicating like parts in the several figures.

This invention relates to heat-responsive devices and particularly to such devices of this general class as have means for normally retaining a member against displacement and for releasing the member to permit such displacement in response to the action of heat. Such devices are used in many different kinds of apparatus, among which may 15 be mentioned the sprinkler heads of automatic fire extinguishing systems, automatic fire alarms, and mechanism for controlling the operation of fire doors. Devices of this character usually include one or more members subject to stress and held normally in place by a resistance member comprising different parts united by fusible material such as solder. A difficulty with such devices, as heretofore commonly used, arises 20 from the fact that substantially the entire strain to which the resistance member is subjected is thrown upon the soldered joint, and many well known factors contribute to render the strength of such joints variable 25 and uncertain. In consequence damage has sometimes resulted, as by the accidental release of a valve in a sprinkler system. With the object, moreover, of guarding against such accidents it has been the practice to use 30 a much larger mass of fusible material in the resistance member than would be necessary if the strength of the soldered joint were a certain factor, thereby rendering the devices in many cases less quickly responsive 35 to the action of heat than is desirable.

It is an object of this invention to provide a simple, durable and readily assembled construction in which the normal stability of the parts of a device of this character will be 40 practically insured, and in which only a comparatively small quantity of fusible ma-

terial will be necessary to insure such stability, thus avoiding accidents, widening the field of utility of such devices, and rendering them more sensitive and more quickly 55 responsive to the action of heat than heretofore. As one means of attaining the desired end, the illustrative embodiment of the invention comprises a novel construction and arrangement whereby a large portion of 60 the strain upon the resistance member is sustained by means other than the fusible material. In the construction shown a strut is arranged in such relation to different parts of the resistance member as to sustain a large 65 portion of the force applied to the member while leaving a small portion of such force effective with a tendency to separate the parts laterally, and it is only this small component of the force that the fusible material 70 is required to resist. Important features of novelty reside in the construction and relative arrangement of the different portions of the device and in the relation of the fusible material to the different parts. 75

A further feature of the invention resides in a novel construction insuring a high degree of strength in the fusible joint uniting different parts of a resistance member. In the application of the invention to a resistance member the parts of which are constrained to move relatively in a definite direction in separating from each other the desired object is attained by providing the parts with opposed soldered surfaces extending in such relation to the direction of relative separating movement of the parts that it is only after a substantial extent of such movement has taken place that there can be any material increase in the distance 80 between said surfaces. In the illustrative construction one of the parts of the resistance member comprises a portion of generally cylindrical contour arranged to lie between opposite side walls of the other part which extend in substantially parallel relation to the direction in which the parts must move relatively in separating, and the solder uniting the parts is disposed between said walls and the opposed surfaces of the inner part. It 85 will be evident that in such a construction the initial relative separating movement of 90 95

the parts takes place without any material increase in the distance between portions of the opposite side surfaces of the inner member and the adjacent opposed surfaces of the outer member, the force tending to rupture the solder being effective in a direction or directions substantially parallel to these portions of the soldered surfaces. It will be readily recognized that a joint of this character is much stronger and more assuredly effective than a joint of the usual construction in which there is nothing other than the solder to restrain the adjacent soldered surfaces from immediate lateral separation.

15 While the construction herein shown includes also the strut hereinbefore described for resisting a portion of the force applied to the member, and while important advantages are inherent in such a combination, it will be understood that a construction embodying a fusible joint of this character has advantages irrespective of the use of such a strut, and the invention in its broader aspects is not limited to a combination of these 20 different features.

25

The invention is herein shown in its application to valve controlling means suitable for use on automatic sprinklers, but it should be understood that the invention is not limited to the illustrative application but is susceptible of a variety of uses in various kinds of apparatus.

30 The novel features of the invention, including certain more important details of construction and combinations of parts, will now be described with reference to the accompanying drawings and pointed out in the claims.

35 In the drawings,—

40 Fig. 1 is a vertical transverse section through a water supply pipe and an automatic sprinkler provided with valve retaining means in which the invention is embodied.

45 Fig. 2 is a vertical section through one of the resistance members shown in Fig. 1.

Fig. 3 is a view similar to Fig. 2 showing the parts in partially separated relation.

50 Fig. 4 is a perspective view of the parts seen in Figs. 2 and 3 in disassembled relation, and

Fig. 5 is a cross-section on the line 5—5 of Fig. 2.

55 The construction shown in Fig. 1 comprises a nozzle member 2 threaded into an opening in a water supply pipe 4 adapted to hold water under pressure. Seated on the opening in the nozzle is a valve 6, and extending upwardly from the member 2 are arms 8 which are joined at their upper extremities and provided with an opening in which is threaded an abutment member 10, this member being positioned in line with the axis of the nozzle opening. In order to 60 hold the valve normally in closed posi-

tion the device, in the construction shown, is provided with a bar 12, the opposite end portions of which project at opposite sides of the device, this bar having intermediate between its ends projections 14 which serve 70 as fulcrums for levers 16 and 18 arranged respectively in engagement with the valve 6 and the abutment 10. The levers 16 and 18 at their outer ends are connected to the corresponding ends of the bar 12 by resistance members or links, the construction of which will be hereinafter described. When the parts are in assembled relation, as shown in Fig. 1, the abutment 10 is screwed down to bring pressure to bear through the levers 16 and 18 and the bar 12 upon the valve 6 in order to hold the valve closed. It will be evident that in this construction the pressure of the abutment 10 upon the inner end 75 of the lever 18 and of the valve 6 upon the inner end of the lever 16 tends to force the outer ends of the respective levers and the corresponding ends of the bar 12 apart, and that the links connected to the outer ends of the levers and the bar serve to hold the 80 levers and the bar against displacement. This general construction forms the subject-matter of my prior Patent No. 1,323,893, granted on Dec. 2, 1919.

85 The link or resistance member herein shown at each side of the device consists of two separate parts 20 and 22, positioned side by side in substantially parallel relation to each other and to the direction of the force applied to the member, and a strut 24 positioned normally between the parts, as shown in Fig. 2. The part 20 has a substantially cylindrical portion 26 constructed to fit within a corresponding recess 28 in the part 22, the wall of said recess being of generally cylindrical contour with its axis substantially parallel to the direction of the force applied to the link, and the cylindrical portion 26 is cut away or recessed to provide a sloping surface 30 in engagement with 90 which the strut 24 lies when the parts are assembled, and also a ledge or abutment 32 to engage one end of the strut. The part 22 has an opening 34 to receive the lower end portion of the strut 24 and 95 to provide an abutment 36 for the lower end of the strut, this abutment being opposed to the ledge or abutment 32 on the part 20. When the parts are assembled, as shown in Fig. 2, with the strut 24 lying 100 against the inclined surface 30 of the member 26 and in engagement at its opposite ends with the abutments 32 and 36 respectively, in which position the longitudinal axis of the strut represented by a line connecting its active abutting faces is inclined to the direction of the force applied to the link, fusible material 38 such as solder is applied in position to hold the parts against 105 separation. In the construction shown in 110

Fig. 2, the solder has been applied in the opening 34 and has been permitted to run in between the strut 24 and the adjacent portions of the parts 20 and 22 and between the opposed surfaces of these parts as far as the edges of the part 22. When a pair of links have been prepared in this manner, they are hooked over the ends of the levers 16 and 18 and the bar 12 assembled as shown 10 in Fig. 1, and the abutment 10 is screwed down, thus subjecting the bar and the levers to stress which tends to separate the outer end portions of the levers from the corresponding end portions of the bar. The 15 links, however, serve to hold the levers and the bar normally against relative displacement, and in consequence the valve 6 is held effectively upon its seat.

The arrows *a* and *b* in Fig. 2 indicate the 20 directions of the forces applied to the opposite ends of the link when the parts of the device are assembled as shown in Fig. 1. These forces, however, are for the most part counteracted by the strut 24, which prevents 25 direct relative movement of the adjacent portions of the parts 20 and 22 in parallel relation to the directions of said forces. By reason of the relatively offset relation of the abutments 32 and 36 laterally of the link, 30 and the incline of the longitudinal axis of the strut 24 with respect to the directions of the forces applied to the opposite ends of the link, a small portion of these forces is effective with a tendency to cause lateral separation 35 of the adjacent portions of the parts 20 and 22, the two parts thus tending to swing apart in the directions of the arrows *c* and *d* under the influence of the strut which is adapted to act as a rocker to separate the 40 parts, and it is only this comparatively small portion of the force applied to the link that the solder 38 is required to sustain. Danger of accident resulting from premature breakage of the joint is therefore rendered practically negligible; and since such security 45 against accident requires only a comparative small quantity of solder in the joint, prompt action of the device to effect the release of the valve under the influence of abnormal heat is rendered certain.

By reference particularly to Fig. 5 it will be seen that a portion of the solder between the parts 20 and 22 lies at opposite sides of the substantially cylindrical member 26 and between this member and the adjacent embracing surfaces of the part 22, the walls of the latter part being extended a considerable distance laterally of the link in substantially parallel relation to the direction 55 of relative lateral separating movement of the parts. It will be evident that with the parts constructed and arranged as shown and described no separating movement of the parts 20 and 22 can take place 60 without causing a substantial relative move-

ment of portions of the adjacent surfaces of the respective parts at opposite sides of the resistance member during which the distance between said surfaces will not be materially increased. With the fusible material between surfaces constrained to move relatively in such relation, a high degree of strength in the joint is insured. 70

A further advantage in the use of the construction shown, aside from the important advantage of its simplicity, arises from the fact that the solder is for the most part, in the interior of the link and thus substantially protected from accidents such as might alter undesirably its normal degree 80 of sensitiveness.

While the invention is herein shown as embodied in a link constructed to resist forces applied and directed in the manner illustrated and described, it will be understood that the essential principles of the invention, in its broader aspects, are not restricted to this particular illustrative application. It should also be understood that the terms "fusible" and "non-fusible" are 90 used herein in a relative and not an absolute sense.

Having described the invention, what I claim as new and desire to secure by Letters Patent of the United States is:

1. In a device of the class described, a resistance member comprising two parts arranged side by side, one of said parts having an abutment thereon and the other having an opening extending laterally therethrough, and adapted to admit fusible material between the parts, a strut substantially inclosed between said parts and arranged for opposite engagement with said abutment and with a wall of said opening respectively 100 and in such relation to the parts as to tend to separate them laterally through the force applied to the member, and fusible material for holding the parts normally against separation. 105

2. In a device of the class described, a resistance member comprising two parts arranged side by side, one of said parts having a recess extending only partially therethrough to provide an abutment and the other having an opening extending laterally therethrough to direct fusible material in said recess, a strut between said parts arranged for opposite engagement with said abutment and with a wall of said opening respectively and in such relation to the parts as to tend to separate them laterally through the force applied to the member, and fusible material in said opening and between the parts for holding them normally against separation. 115

3. In a device of the class described, a resistance member comprising parts arranged side by side, one of said parts having a recess therein to provide an inclined surface and 130

- an abutment at one end of said surface, the other part having an opening extending therethrough providing an abutment opposed to the abutment on said first named part, a strut extending lengthwise along said inclined surface with its opposite ends in engagement respectively with said abutments, and fusible means for holding said parts and the strut normally in assembled relation.
- 10 4. In a device of the class described, a resistance member comprising parts arranged laterally adjacent to each other and one of which partially embraces the other, said parts being formed to provide a recess between them, a strut positioned in said recess with its opposite end portions in engagement respectively with the different parts and with its longitudinal axis inclined to the direction of the force applied to the resistance member to effect lateral separation of the parts in response to said force, the strut being smaller in cross section than said recess, and fusible material in said recess adjacent to the strut for normally holding the parts 25 against lateral separation, one of the parts having an opening therethrough communicating with a portion of the recess which is adjacent to the strut for admitting the fusible material when the different portions of 30 the member are assembled.
5. In a device of the class described, a resistance member comprising two parts, one lying within a recess in the other, a strut between said parts with its longitudinal axis 35 inclined to the direction of the force applied to the member to effect lateral separation of the parts in response to said force, and fusible material in said recess for normally holding the parts together.
- 40 6. In a device of the class described, a resistance member comprising parts arranged side by side in substantially parallel relation with one of said parts positioned within a recess in the other part, a strut comprising a bar 45 extending lengthwise between said parts at an angle to the direction of the force applied to the member with its opposite end faces in abutting relation to the respective parts, and fusible material between said parts and in 50 contact with said strut for holding said parts and the strut normally in assembled relation.
7. In a device of the class described, a resistance member comprising two parts arranged longitudinally side by side with a concave recess in the side of one part and a convex portion on the other part to lie in said recess, a strut inclined laterally of said parts to effect lateral separation of the parts 60 through force applied longitudinally of the member, and fusible material between the concave and convex portions of the respective parts and at substantially opposite sides of the inner part to hold the parts normally 65 against lateral separation.
8. In a device of the class described, a resistance member comprising two parts arranged to be subjected to force tending to move them relatively and positioned side by side in substantially parallel relation to the 70 direction of said force, one of said parts having a lateral recess with a wall of generally cylindrical contour partially embracing the other part, a strut inclined to the direction of said force with its opposite ends 75 engaging the different parts respectively to constrain the parts to separate laterally in response to said force, and fusible material in said recess substantially at opposite sides 80 of the inner part for holding the parts normally against relative movement.
9. In a device of the class described, the combination with members subject to a force tending to move them relatively apart, of a resistance link comprising two parts arranged side by side and connected respectively to said different members, one of the parts having a concavely curved recess in one side within which a portion of the other part is received, a strut in said recess 90 and between the parts arranged with its longitudinal axis inclined laterally of the link to prevent said parts from moving relatively in the direction of the force applied to the link except with a component of relative movement in a direction at an angle to the direction of said force, and fusible means for normally preventing relative movement 95 of the parts in said angular direction.
10. In a device of the class described, a resistance member comprising two parts arranged to be subjected to force tending to move them relatively, one of said parts having a contour convexly curved in transverse section and the other part having a lateral 100 recess to receive a portion of said first named part, means tending to separate the parts laterally in response to the force applied to the member, and fusible material lying between the adjacent surfaces of said parts at 105 substantially opposite sides of said convexly curved part for holding the parts normally against separation.
11. In a device of the class described, a resistance member comprising two parts arranged to be subjected to force tending to move them relatively, one of said parts having in one side a recess with a boundary wall 110 curved about an axis substantially parallel to the direction of the force applied to the member and extended laterally of the member for partially embracing the other part and said other part having a portion constructed to lie in said recess, a strut arranged to bear oppositely against said parts 115 and to sustain the major portion of the force applied to the member with its longitudinal axis inclined laterally of the member to effect relative lateral separation of the parts 120 in response to said force, and fusible mate- 125
- 130

rial between the adjacent surfaces of said parts substantially at opposite sides of the portion in said recess to hold the parts normally against separation.

5 12. In a device of the class described, a resistance member comprising two parts extending lengthwise in substantially parallel relation to the direction of force applied to the member and one of which partially incloses the other, a device for preventing relative lengthwise movement of said parts except with a component of relative lateral movement, the inclosing part having surfaces at opposite sides of the inner part extending laterally of the inner part in generally parallel relation to the direction of such relative lateral movement of the parts, and fusible material between said surfaces and the inner part for holding the parts normally against relative movement.

10 13. In a device of the class described, a resistance member comprising two parts one of which is arranged partially to embrace the other with the opposed surfaces of the parts at opposite sides of the member so disposed as to require a substantial extent of relative lateral separating movement of the parts before materially increasing the distance between said surfaces, a strut between 15 said parts arranged to sustain a portion of the force applied to the member with its longitudinal axis inclined to the direction of said force to cause the parts to separate laterally in response to said force, and fusible material between said opposed surfaces for

normally preventing separation of the parts of the member.

14. In a device of the class described, a resistance member comprising two parts one of which has a portion of substantially cylindrical contour extending lengthwise in substantially parallel relation to the direction of the force applied to the member and the other being constructed for partially embracing said cylindrical portion, said parts having recesses in their opposed faces to provide oppositely disposed abutments, a strut lying in said recesses at an angle to the direction of the force applied to the member, and fusible material for holding 40 said parts and the strut normally assembled. 45

15. In a device of the class described, a resistance member comprising parts arranged to be subjected to a force tending to separate them, a member arranged to bear 50 oppositely against the respective parts and to act as a rocker to force them relatively apart in a direction substantially at right angles to the direction of said force, one of the parts partially inclosing the other and 55 having opposite side walls with surfaces extending in substantially parallel relation to the direction in which the parts are constrained to move relatively by the action of said rocker, and fusible material between 60 said surfaces and the inner part to hold the parts normally against relative movement. 65

In testimony whereof I have signed my name to this specification.

BENJAMIN F. MAYO.

Certificate of Correction.

It is hereby certified that in Letters Patent No. 1,445,702, granted February 20, 1923, upon the application of Benjamin F. Mayo, of Salem, Massachusetts, for an improvement in "Heat-Responsive Devices," errors appear in the printed specification requiring correction as follows: Page 3, line 117, claim 2, after the word "material" insert the words *between the parts, a strut*, and line 118, strike out the words "a strut between said parts"; and that the said Letters Patent should be read with these corrections therein that the same may conform to the record of the case in the Patent Office.

Signed and sealed this 29th day of May, A. D., 1923.

[SEAL.]

KARL FENNING,
Acting Commissioner of Patents.
